SHORT WAVE CONVERTER

Leo J. Hruska, Merchantville, N. J., assignor to
 Radio Corporation of America, a corporation
 of Delaware

Application December 28, 1935, Serial No. 56,409

3 Claims. (Cl. 250—20)

My invention relates to radio receivers. Specifically my invention relates to a radio receiver in which a single thermionic tube is used as an oscillating detector, a super-regenerative detector, and a modulator-converter which supplies modulated intermediate frequency currents for superheterodyne reception.

I am aware of the circuits employed for regenerative, super-regenerative, and superheterodyne reception of radio frequency signals. I propose to combine several separate functions in a single thermionic tube. In the preferred form a single triode may be used. My invention not only simplifies the circuits, and uses a single tube, but it also permits single control operation with a single variable element.

One of the objects of my invention is in the design of a single triode tube as an oscillating detector, a super-regenerative detector, and a modulator-converter.

Another object of my invention is to provide a super-regenerative-superheterodyne receiver with a single tuning element.

A further object is the design of a very sensitive ultra short wave receiver which converts and modulates the ultra short waves to waves of a different length.

Additional objects will be apparent from the accompanying specification, drawing, and claims.

Reference to the drawing, which is an illustration of one embodiment of the circuits employed in my invention, is the best means of understanding the invention. In this drawing, an antenna 1 is coupled through a capacitor 3 to an inductor 5. The junction between the capacitor 3 and inductor 5 is connected to the grid 7 of a thermionic tube 9. The cathode 11 of the thermionic tube 9 is grounded. The cathode may be of the filament, or unipotential type. Batteries for heating this cathode, or the cathodes of other tubes about to be described, have been omitted for simplicity. Any suitable current source may be used, as is well understood by those skilled in the art.

The anode 13 of tube 9 is connected to one terminal of an inductor 15. The other terminal of this inductor 15 is connected through an inductor 17 to the positive terminal of a B battery 19, or the like. The negative terminal of the B battery is grounded. The battery may be bypassed by a capacitor 21. A variable capacitor 23 is connected between the grid 7 and the anode 13. A second capacitor 25, which may be variable, is connected from the lower terminal of the inductor 5 to the lower terminal of the inductor 15. This capacity acts as a bypass for ultra high frequency

currents. It may be used to tune or control feed-back.

Neglecting for the moment the direct current path from grid 7 to ground, with properly chosen values of inductance and capacitance, the tube and circuits thus described will operate as an ultra high frequency oscillator. By way of example, ultra high frequencies are from 30 megacycles to 100 megacycles and upward. The inductor 15 is chosen so that it will offer an inductive reactance to currents of the received frequency to insure a strong regenerative feedback. The single variable tuning capacitor 23 acts as the tuning element which controls the frequency of the received signal representing currents and the frequency of the circuits as a local oscillating detector.

I shall now describe the circuits for the quench frequency oscillator. The quench frequency is the low frequency potential which is applied to the grid of a regenerative detector to obtain super-regenerative operation. Super-regenerative operation is well known to those skilled in the art. A recent discussion of this type of operation is found in the Proceedings of the Institute of Radio Engineers, vol. 23, Number 8, page 841 of August, 1935.

The quench frequency oscillator circuits are from the grid 7 through inductor 5, through a radio frequency choke 27 to a grid resistor 29—grid capacitor 31 combination. The lower terminal of the grid resistor-grid capacitor combination is connected to the upper terminal of a tank circuit 33. The tank circuit 33 is composed of a semi-variable capacitor 35 and an inductor 37. The lower terminal of the tank circuit is grounded.

The anode circuit is composed of the inductors 15 and 17, and capacitor 21. The inductor 17 is mutually coupled to the inductor 37 as indicated by mutual inductive coupling M. Although I have illustrated the coupling as magnetic, any type of regenerative feedback may be employed.

Having thus briefly described the quench oscillator circuits, their operation and adjustment will be set forth. I prefer to first short circuit the ultra high frequency inductors 5 and 15. The coupling between the anode circuit inductor 17 and the grid circuit inductor 37 is adjusted to a value which causes local oscillations. The semi-variable capacitor 35 of the tank circuit is adjusted until the desired quench frequency oscillations are produced. The frequency, which I prefer, is that of a cleared channel just below the present broadcast band; for example, 500 kilo-

cycles. The quench frequency chosen must also be selected with the intermediate frequency and second detector circuits in mind because these frequencies are preferably substantially identical. 5 After the desired quench frequency oscillations have been obtained, the variable adjustments may be fixed as no further adjustments are normally required. The short circuiting conductors, previously described, are removed from the inductors 10 5 and 15. These inductors are not inductively coupled as illustrated, but, if desired, inductive coupling may be employed.

The radio frequency choke 27 and bypass capacitor 25 form a net work which freely passes 15 currents of ultra high frequency between inductor 5 and inductor 15 and prevents the ultra high frequency currents from passing to the quench frequency circuits. The inductors 5 and 15 which offer effective inductive reaction at the ultra high 20 frequencies, offer very low and negligible reactance at the lower or quenching frequency. Likewise the radio frequency choke 27 and bypass capacitor 25 offer very small or negligible reactance to the quench frequencies.

25 Although I do not wish to be limited to any precise theory of operation, I believe the operation is as follows: The received signal representing currents are impressed on the grid electrode of the triode. These incoming currents are detected by the ultra high frequency oscillating detector. The usual frequencies resulting from demodulation are present.

30 The detector is also being supplied with currents of the quench frequency. These currents serve two purposes: First, the quench currents provide the well known super-regeneration operation and thereby greatly increase the sensitivity of the detector. Second, the modulation component of the received signal is impressed on the 35 quench frequency currents, thereby modulating these currents.

40 In any event a modulated carrier current oscillating at the quench frequency appears across the quench frequency anode inductor 17. These modulated carrier currents may be impressed on the input of an amplifier 39 through a small coupling capacitor 41. The input to the amplifier 39 is preferably tuned to the quench frequency by a tank circuit 43. The output of the amplifier 45 is likewise tuned by a tank circuit 45. The output tank circuit 45 is coupled to a resonant circuit 47. Across this resonant circuit is connected a suitable detector 49.

45 The detector 49 demodulates the modulated carrier frequency currents which have been amplified by the amplifier 39. The output circuit of the detector may include telephone receivers 51 or the like. In place of telephone receivers 56 the output may be connected to an audio frequency amplifier and hence to a loud speaker, cathode ray tube, or any signal indicating device.

50 Although I prefer to operate the intermediate frequency amplifier at the quenching frequency,

it is possible to operate at a harmonic of the quenching frequency. In a similar manner, I have fixed the intermediate frequency and operated the quench oscillator at a sub-harmonic thereof. Other modifications within the scope of my invention will occur to those skilled in the art. The foregoing specification is by way of example and not a limitation on my invention, which is only limited as required by the prior art and appended claims.

5 10 15 20 25 30 35 40 45 50 55 60 65 70 75 80 85 90 95 100

I claim as my invention:

1. A radio receiving system comprising a thermionic tube having grid, cathode, and anode electrodes, a first pair of circuits effectively connected to said thermionic tube for generating and detecting oscillatory currents of ultra high frequency, means for tuning said circuits over a range of ultra high frequencies, a second pair of circuits serially connected to said first pair of circuits for generating quenching oscillations of a substantially lower frequency than said ultra high frequencies, means for preventing said ultra high frequency currents from entering the said pair of lower frequency circuits and permitting currents of said quenching frequency to be applied to said grid, and means for detecting modulated carrier currents generated by said thermionic tube.

2. In a radio system an oscillating detector having a single variable element for tuning over a range of ultra high frequencies, circuits for generating currents of a substantially lower frequency connected to said oscillating detector, means for bypassing currents of said ultra high frequency around said lower frequency circuits, means offering high reactance to said ultra high frequency currents and low reactance to said low frequency currents connected in said high frequency circuits, means whereby said low frequency currents are applied to said oscillating detector to quench said ultra high frequency currents, and means for detecting the resulting modulation currents.

3. In an apparatus of the character described, a pair of oscillatory circuits, one of said pair of oscillatory circuits tunable over a range of ultra high frequencies, the other of said pair tuned to a single frequency substantially lower than said ultra high frequencies, a single triode tube effectively connected to said circuits, means for generating oscillatory currents within said tube and circuits of said ultra high and relatively low frequencies, means for preventing said circuits from interacting on each other and for insuring the combining of currents of each mentioned frequency within said tube, means for impressing modulated signal frequency currents on said oscillating detector whereby a resultant modulated carrier of a different frequency is generated by said tube, and means for detecting said resultant modulated carrier.

LEO J. HRUSKA.
